UNITED STATES PATENT OFFICE

2,439,265

INTERNAL-COMBUSTION ENGINE

William M. Schroeder, Waukegan, Ill.

Application May 22, 1944, Serial No. 536,770

1 Claim. (Cl. 123—58)

1

This invention relates to improvements in internal combustion engines of that type embodying a power shaft, longitudinally opposed groups of cylinders disposed about said shaft parallel thereto, pistons in said cylinders, common piston rods interconnecting the pistons of opposed cylinders, a cylindrical rotor member fixed on said shaft intermediate said groups of cylinders and having a continuous cam groove in its cylindrical surface, and means on said piston rods for engaging said cam groove so that reciprocation of the pistons effect rotation of said shaft.

An important object of the present invention is to generally simplify and improve the construction of internal combustion engines of the above type.

A more specific object of the present invention is to provide, in an engine of the above kind, improved means for forming explosive charges and controlling the admission of said charges to the engine cylinders.

Another specific object of the invention is to provide, in an engine of the above kind, simple and efficient means for controlling and effecting the exhaust of spent gases from the engine cylinders.

More specific objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a central longitudinal sectional view of an internal combustion engine constructed in accordance with the present invention.

Figure 2 is an enlarged transverse section taken on line 2—2 of Figure 1.

Figure 3 is a transverse section taken on line 3—3 of Figure 1.

Figure 4 is an end elevation looking toward the left of Figure 1.

Figure 5 is a central sectional view through one of the heads of the housing of the engine and taken substantially on the plane of line 5—5 of Figure 4.

Figure 6 is an elevational view of one of the cam discs employed for opening the intake valves of the cylinders of each group, and

Figure 7 is a fragmentary elevational view showing an intermediate portion of the power

shaft and the cylindrical rotor member fixed thereon.

Referring in detail to the drawings, the present engine includes a power shaft 5, longitudinally opposed groups of cylinders 6 and 6a disposed about the shaft 5 parallel thereto, pistons 7 and 7a in said cylinders, common piston rods 8 interconnecting the pistons 7 and 7a of opposed cylinders 6 and 6a, a cylindrical rotor member 9 fixed on the shaft 5 intermediate the groups of cylinders 6 and 6a and having a continuous cam groove 10 in its cylindrical surface, and means 11 on the piston rods 8 for engaging the cam groove 10 so that reciprocation of the pistons 7 and 7a cause rotation of shaft 5.

In accordance with the present invention, the groups of cylinders 6 and 6a are carried by and arranged within opposite ends of the elongated cylindrical body 12 of a housing that is closed at its ends by hollow removable heads 13 and 13a which respectively close the outer ends of the cylinders 6 and the cylinders 6a. The body of the housing 12 is preferably composed of three sections bolted together, as at 14, and having partitions 15 and 15a bolted between the intermediate section and each end section and respectively closing the inner ends of the cylinders 6 and of the cylinders 6a. This defines a chamber between the groups of cylinders, and fixed on the shaft 5 within this chamber is the rotor member 9.

Rigidly fixed at 16 within each head 13 and 13a and spaced from the walls of said head is a hollow circular casing 17 within which is arranged a cam disc 18 that is fixed on shaft 5 and has a plurality of cams 19 on the inner face thereof. The inner wall of each head 13 and 13a is provided with intake ports 20 for the respective cylinders of the associated group, and these ports are normally closed by spring seated poppet valves 21 whose stems extend into the adjacent casing 17 in proper position to be operated by the proper cam 19 of the associated cam disc 18. Thus, as shaft 5 is rotated, the cam discs 18 rotate therewith and cause successive opening of the intake valves 21 in proper timed relation. A pipe 22 conveys fuel under pressure to each head 13 and 13a, while another pipe 23 conveys compressed air to each of said heads. The compressed air and fuel supplied to each head combines in the latter to form explosive charges whose admission to the cylinders is controlled by the valves 21. Thus, the explosive charges are supplied under pressure to the cylinders and suction of the pistons is not

relied upon for drawing the explosive charges into the cylinders. The fuel may be supplied under pressure through the pipes 22 from any suitable source, and the compressed air may be supplied to pipes 23 from any suitable source.

The present engine is preferably of the air cooled type, and for heat dissipating purposes, the body of the housing 12 is preferably provided with radial longitudinally extending heat-dissipating fins 24. Also, circulation of air through the housing about the cylinders may be permitted by providing the end sections of said housing with numerous openings or perforations, as indicated in Figure 2 at 25.

Each cylinder is provided with an exhaust port 26 at a point so that it will be uncovered as the associated piston approaches its inward limit of movement. The exhaust ports of opposed cylinders are connected by rearwardly directed pipes 27 with a common exhaust manifold 28 that extends alongside the housing parallel with the shaft 5 and is open at its ends. The front end of each exhaust manifold 25 is preferably flared, as at 29, so that upon forward travel of vehicle equipped with the present engine, air will be scooped into the manifolds. As the air flows at high velocity rearwardly through the manifolds 28, it ejects the exhaust from the associated cylinders 6 and 6a as their exhaust ports are uncovered. A fuel charge admitted into a cylinder at this time also helps to force the spent gases from the associated cylinder. However, the pistons will again cover the exhaust ports in time to prevent loss of the explosive mixture from a cylinder into which the mixture has been admitted. Any suitable means may be provided for igniting the explosive charges admitted to the cylinders, the ignition system including spark plugs 30 for the respective cylinders. Also, the shaft 5 may be equipped with fly wheels 31 at the inner ends of the groups of cylinders.

An engine constructed in accordance with the present invention is especially serviceable for use upon aircraft, and when the engine is so used, the propeller 32 may be fixed directly upon a projecting end of the shaft 5, as shown in Figure 1.

The timing of the admission of explosive charges and the ignition thereof will depend upon the cycle principle upon which the engine is constructed to operate. It will be evident, however, that upon turning shaft 5 by any suitable means, the engine may be started. When in operation, a charge will be compressed and ignited in each cylinder 6 when spent gases have exhausted from the opposed cylinder 6a, and the charge in said opposed cylinder will be com-

pressed during the power stroke of the piston in the first-named cylinder. This action will take place alternately around the groups of opposed cylinders so that power is substantially continuously applied to shaft 5 for driving the latter.

From the foregoing description, it is believed that the construction and operation, as well as the advantages of the present invention, will be readily understood and appreciated by those skilled in the art. Minor changes in details of construction illustrated and described are contemplated, such as fairly fall within the spirit and scope of the invention as claimed.

What I claim as new is:

In an internal combustion engine having a rotatable shaft, a plurality of cylinders arranged with their axes parallel to said shaft and grouped around said shaft, pistons reciprocable in said cylinders, and means interconnecting said pistons and said shafts for effecting rotation of said shaft upon reciprocation of said pistons in said cylinders, the combination of a hollow cylinder head for said cylinders forming a fuel and air mixing chamber therefor, a group of poppet valves cooperating with said head for controlling the flow of combustible mixture to said cylinders from said chamber, said valves having stems arranged with their axes parallel with and about the axis of said shaft, and a cam fixed for rotation with said shaft and having a cam face thereof disposed normal to the axes of said stems and operatively engaging the same, a hollow casing rigidly mounted in and spaced from the walls of said head, said cam being arranged within said casing, and the stems of said poppet valves projecting into the casing.

WILLIAM M. SCHROEDER.
